UNITED STATES PATENT OFFICE.

ALLEN A. TIRRILL, OF SCHENECTADY, NEW YORK, ASSIGNOR TO GENERAL ELECTRIC COMPANY, A CORPORATION OF NEW YORK.

RELAY.

1,101,670.

Specification of Letters Patent. Patented June 30, 1914.

Application filed April 27, 1908. Serial No. 429,326.

To all whom it may concern:

Be it known that I, ALLEN A. TIRRILL, a citizen of the United States, residing at Schenectady, in the county of Schenectady, 5 State of New York, have invented certain new and useful Improvements in Relays, of which the following is a specification.

This invention relates to relays and particularly to an improved relay for use in 10 the so-termed "Tirrill" systems of voltage regulation.

As is well known, voltage regulators of the form shown in my Patent #726,234 operate by opening and closing a shunt around 15 a resistor included in the shunt field circuit of a generator. The action is automatic, being effected by one or more relays controlled by a main magnet which is responsive to changes in the line voltage and which controls a pair of contacts in a derived circuit including the windings of the relays.

The object of this present invention is to provide an improved relay which shall be capable of simultaneously opening and 25 closing any number of shunt circuits, and the special construction by which this is accomplished forms the subject matter of this application. In brief, the relay has a circular winding, combined with a plurality 30 of separate cores, each of which cooperates with its own armature and contacts to control a particular circuit. As these various contact-making armatures operate in unison, and each contact shunts by its closure a certain amount of resistance, it follows that 35 a greater total amount of resistance can be controlled by a magnet of this construction and, therefore, the use of my improved relay greatly enlarges the capacity of the 40 Tirrill regulator and makes it available for the regulation of much larger units or groups of units, than was heretofore possible.

In the accompanying drawings, Figure 45 1 is a diagram of a system using a voltage regulator equipped with my improved relay; Fig. 2 is a front elevation of the relay on a larger scale; and Fig. 3 is a radial sectional elevation of said relay.

50 In order that the application and operation of my relay may be clear. I will first refer to Fig. 1 and later describe the actual construction as illustrated in Figs. 2 and 3.

Referring to Fig. 1 it will be seen that it shows two three-phase alternating-current generators 3, 4, feeding into bus bars 5, from which a load circuit 6 is led. The field coils of these generators are supplied with direct current from the buses 7 which are fed by the exciters 8, 9, 10. In series 55 with the shunt field coils of each of these exciters is a resistor, numbered 11, 12, 13 respectively. A shunt circuit 14 is connected around the resistor 11, containing a pair of contacts 15, which are shunted by a condenser 16. The resistor 12 is divided into two portions or sections, each of the same ohmic resistance, and each section is shunted by circuits 17, 18, respectively, each controlled by a pair of contacts 19, 20, respectively. In the same way, the resistor 13 is divided into two equal sections, one of which is shunted by the circuit 21 and contacts 22, and the other by the circuit 23 and contacts 24. Each pair of contacts is shunted 60 by a condenser 16. It is now in order to describe the relay of which these contacts form a part. It consists preferably of two differentially-wound coils 25, 26 (Figs. 1 and 3) arranged one in front of the other as one 65 looks at the relay. The permanently connected winding 27 in the coil 25 runs in the opposite direction to the similar winding 28 in the coil 26, while the differential winding 29 in the coil 25 runs in the opposite direction to the differential winding 30 in the coil 26. The reason for this is apparent upon inspection of Fig. 3, which clearly shows the E-shaped core 31 applied 70 to the two coils and receiving them between 75 its legs, the middle pole or leg serving as a spacer for said coils. The opposite directions of the windings insures the proper magnetization of this core so that its inner and outer poles will be of the same polarity 80 and the opposite of that of the middle pole. By this arrangement I am able to get a maximum pull on each armature, for it will be clear that each pole of the magnetized core will attract the armature relays. If 85 the coils were wound in the same direction there would be no resultant pole at the center of the E-shaped core and the middle projection would have no attracting effect. An armature 32 is pivoted in a bracket 33 90 secured adjacent to the inner pole and by

this location of the pivot a long bearing is afforded to prevent twisting of the armature.

A lever arm 34 is secured to the armature and extends in behind the inner coil to a point where it can be attached to the inner end of a spring 35 which is adjustable as to tension by means of a screw 36 supported in a bracket 37 which is bolted to the core. 5 The outer end of the armature carries a contact stud 15 which coöperates with a similar stud mounted on the outer end of a light spring 38 secured to a standard 39 securely mounted on the panel 1. The outer end of 10 said standard is preferably slotted, to receive the screws 40 by means of which the spring 38 is attached to it; the slot affording a possibility of adjustment. A flexible conductor 41 runs from the armature to a 15 low stud 42 on the panel, and current can be led to the standard and this low stud by screws which pass through the panel and afford means for connecting the terminals of one of the shunt circuits 14, 17, 18, 21 20 or 23.

As previously stated, any desired number of cores and contacts can be applied to the coils; in the drawings I have shown five, 25 symmetrically arranged around the coils, which are preferably annular. The various cores are spaced by a ring 43.

A conductor 44 (Fig. 1) runs from the positive exciter bus bar 7 through a resistor 45 to the windings 27 28, their other terminals being connected to the return conductor 46. A branch conductor 47 extends from the conductor 44 to the floating contacts of the main control magnet and thence to the windings 29 30, whose other terminals 40 are connected with the return conductor 46.

The main control magnet is shown in diagram in Fig. 1, the direct-current coil 48 being connected across the conductors 44 and 46, through a resistor 49, the magnet being 45 provided with the usual stop core 51 and the movable core 52. The lever 54 connected to said core 52 carries a contact 55 and is normally pulled down by the spring or springs 72 attached thereto. Opposite 50 the magnet 48 is the alternating current magnet 56 which has a movable core 57 attached to a pivoted lever 58 suitably fulcrumed, and carrying a contact 60 which coöperates with the contact 55 on the lever 54; the two constituting the so-called floating main contacts. This magnet has a potential winding 61 connected by means of a potential transformer 62 to the alternating current bus bars 5. It also has a compensating winding 63 which is shown connected to a current transformer 64 located in the load circuit 6. The compensating winding is adjustable by means of the dial switch 65, so that any degree of compensation can 55 be obtained, depending on the line require-

ments. In axial alinement with the alternating current magnet is a dash-pot 66.

The cycle of operations of a regulator equipped with my improved relay is as follows:—First, the shunt circuits across the exciter field rheostats are opened by means of suitable switches 71, and these rheostats are adjusted to a point that will reduce the alternating current voltage considerably below normal. From this the alternating control magnet will be weakened and its core will fall and cause the contact 60 to close upon the upper contact 55. The direct current magnet has been weakened simultaneously with the other, and the spring or springs 72 attached to its lever have pulled down said lever toward the lever of the alternating current magnet. The closure of these floating contacts closes the circuit of the windings 29 30 of the relay, 80 which oppose the permanently connected windings 27 28, and this demagnetizes the relay cores, allowing their armatures to be released and permitting their springs 35 (Fig. 3) to close the relay contacts. Then, 85 by closing the switches in the exciter shunt circuits, and thereby effecting a short-circuiting of the rheostats 11, 12, 13, the voltage of the excitors will immediately rise and cause a rise in the voltage of the generators 3 4. This will strengthen the control magnets, and when the voltage reaches the 90 value for which they have been adjusted the main contacts 55 60 will open, thus breaking the circuit of one set of the relay windings and permitting the permanently connected set to magnetize the cores and open the relay contacts. This throws the full resistance of the resistors 11, 12, 13 into the field 95 circuits of the excitors, which tends to lower the voltage again. This cycle of operations is continued at a high rate of speed, owing to the sensitiveness of the direct current control magnet; and the result is to maintain a steady exciter voltage which will be increased or diminished according to the demands of the system.

From the foregoing, it will be evident that I have herein disclosed an improved form of relay which is particularly adapted to use with a "Tirrill" regulator but whose field of usefulness is by no means so limited. My arrangement is especially desirable where it is necessary to operate a number of relays simultaneously and speedily and where space and cost are essential considerations. By the use of two coils arranged in parallel I have reduced the resistance of the relay and hence for use with a given supply voltage get an increased number of ampere turns and consequently an increased magneto motive force. By winding those coils which are connected in parallel in opposite directions I get a resultant pole at the middle projection of the E-shaped core. This middle 100 105 110 115 120 125 130

projection is therefore useful and aids in attracting the armature instead of being of no advantage magnetically as would be the case were the windings which are connected in parallel wound in the same direction. By placing a plurality of cores on the superposed coils I get an exceedingly compact and inexpensive relay operating a plurality of contacts. By arranging these cores radially with the brackets for supporting the armatures on the outer circumference I am able to make these brackets wider and obtain a more rigid pivoting of the armatures with less opportunity for lateral movement. By using a differential winding I get a faster action with less danger of sticking due to residual magnetism. All these advantages contribute toward making my relay novel, efficient, and reliable.

20 I conceive that various modifications of the exact arrangement herein described might be made which would be within the scope of my invention, and I accordingly do not wish to limit myself to the construction

shown, but seek in the appended claims to cover all such modifications which are properly included in the scope of my invention.

What I claim as new and desire to secure by Letters Patent of the United States, is

1. In a relay, an E-shaped core provided with two coils between its legs, the coils being oppositely wound and connected in parallel so that a resultant pole is produced at the middle leg of the core.
2. A relay comprising two circular coils spaced apart, each coil being made up of two reversely arranged windings, the windings of one coil being connected in parallel with the oppositely arranged windings of the other coil, and E-shaped cores applied to said windings.

In witness whereof, I have hereunto set my hand this 24th day of April, 1908.

ALLEN A. TIRRILL.
